John W. Green, 1039 Capri Drive, Campbell, Calif.

Filed May 1, 1963, Ser. No. 74,693

Term of patent 3½ years

(Cl. D93—3)

FIGURE 1 is a perspective of a jig saw incorporating my new design, showing one side and the front end of the machine.

FIGURE 2 is a rear elevation of the jig saw of FIG. 1.

FIGURE 3 is a front elevation thereof with the handle shown in cross section and with the base and supporting standard omitted for convenience of illustration.

I claim:

The ornamental design for a jig saw, substantially as shown.
